UNITED STATES PATENT OFFICE

GEORGE G. GOING, OF MIDDLETOWN, CONNECTICUT, ASSIGNOR TO REMINGTON TYPE-WRITER COMPANY, OF ILLION, NEW YORK, A CORPORATION OF NEW YORK

TYPEWRITING MACHINE

Application filed October 31, 1927. Serial No. 229,962.

My invention relates to typewriting machines, and more particularly to carriage escapement mechanism and controlling means therefor.

It often occurs that an operator will dwell on the space key, holding it depressed while actuating one or more printing keys, and vice versa. This operation, in many machines heretofore in use, resulted in holding the carriage against letter feed movement at a time when a feed thereof should be effected by the actuated key or keys. As a consequence characters would be "piled", or written one on top of another, or a character would be printed where a space should be provided.

Generally stated, the main object of my invention is to provide an improved means by which this difficulty may be overcome and to provide mechanism of the character specified which is comparatively simple in construction reliable and highly efficient in use and which may be manufactured at comparatively small cost.

A further object of my invention is to provide a construction such as is specified above that may be readily incorporated in existing typewriting machines without changing, or materially changing, the structural features thereof, or the escapement mechanism employed therein.

To the above and other ends which will hereinafter appear, my invention consists in the features of construction, arrangements of parts and combinations of devices set forth in the following description and particularly pointed out in the appended claims.

In the accompanying drawings wherein like reference characters designate corresponding parts in the different views,

Fig. 1 is a side elevation, with parts in section and parts omitted, of a Remington-Noiseless No. 6 machine equipped with the devices of my invention; the view showing the parts as they appear when the space key is held depressed.

Fig. 2 is a like view of the same with some of the parts shown in Fig. 1 omitted, and illustrating the parts as they appear when a printing key is held depressed.

Fig. 3 is a detail, perspective view of the actuating connections from the space key to the dog rocker, together with some of the associated parts; the view showing the parts in normal position.

Figs. 4, 5, 6 and 7 are fragmentary, detail side views showing the trip-off mechanism controlled by the space key at different stages of its operation on the dog rocker; Fig. 4 indicating the normal positions of parts; Fig. 5, the positions of the parts at just about the instant when the trip-off device after having actuated the dog rocker is about to release it for independent return movement; Fig. 6, the positions of the parts after the dog rocker has returned to normal position while the trip-off device remains advanced in its actuated position; and Fig. 7, the positions the parts assume when the trip-off device is just about to clear the dog rocker in returning to normal position without actuating the dog rocker.

Fig. 8 is a detail, fragmentary, top plan view of the carriage escapement devices.

Figs. 9, 10, 11 and 12 are diagrammatic views illustrating the disposition of the escapement devices at different stages of the cycle of movements thereof during a single letter space movement of the carriage.

Fig. 13 is a fragmentary detail rear view, showing the dog rocker, returning spring therefor and some of the associated parts.

Fig. 14 shows in perspective and separated the coacting parts that enter into means for effecting a fore and aft adjustment of the trip-off device.

I have shown my invention embodied, in the present instance, in a No. 6 Remington-Noiseless machine in which the invention may readily be embodied with but few changes in the existing structural features of said machine. Nevertheless, it should be understood that the invention is not restricted to embodiment in such machine but may be employed in different characters of typewriting machines wherever found available.

The present invention has some of the same general objects in view as the inventions disclosed in my Patent 1,691,197, dated 100

June 7, 1927 and my application Serial No. 146,207, filed November 4, 1926, now Patent No. 1,682,330, dated Aug. 28, 1928, although there are distinct advantages which accrue from the present construction. The claims included herein are restricted to features not disclosed in said prior patent and application.

I have shown in the accompanying drawings only so much of a No. 6 Remington-Noiseless machine as is necessary to arrive at an understanding of my present invention in its embodiment therein.

The platen 1 is carried in the usual manner by a case shifting carriage, comprising end plates 2 and a traverse bar 3 supported on crossed anti-friction rollers 4. The carriage is thus mounted to travel from side to side of the machine under the power of a spring drum 5 connected to the carriage through a pull band 6 and under control of the carriage escapement mechanism.

The escapement mechanism comprises a releasable feed rack 7 that normally engages a feed pinion 8 carried by a vertically disposed escapement wheel shaft 9. This shaft is mounted at its upper end in a bearing carried by the case shift frame 10 for vertical case shifting movement therewith. The lower end portion of the shaft 9 is grooved longitudinally at 11 where it contacts with anti-friction rollers 12 carried by the escapement wheel 13. The escapement wheel is supported by a fixed bracket arm 14 so that while the wheel is fixed to turn with the shaft 9, said wheel is supported by its bracket and held against vertical displacement when the shaft shifts independently with the case shifting movement of the carriage.

The dog rocker 15 is mounted at its ends on pivot screws 16 in arms 17 on the same supporting bracket 18 that is provided with the arm 14. A forwardly extending arm 19 on the dog rocker carries on the upper side thereof a normally engaged holding dog 20, pivoted at 21 on said arm and forced to normal position, shown in Fig. 8, by a spring 22. When the carriage is returned to the right without disengaging the feed rack 7, the escapement wheel will turn backward, forcing the holding dog rearward away from the teeth of the wheel against the force of the spring 22. A stepping dog 23 is pivoted at 24 on the under side of the arm 19 of the dog rocker, to receive a limited oscillating movement. This movement of the stepping dog is with the escapement wheel in the direction of its feed and against the force of the light spring 22, and to an advanced position in the opposite direction to which the dog is forced by the spring 22. The means for limiting the oscillation of the stepping dog 23 comprises a bifurcation 26 in the tail of the stepping dog co-

acting with the free end portion of an arm 27 pivoted at 28 on an arm 29 on the dog rocker 15. The pivot 28 is adjustable to different set positions along a slot 30 in the end of the arm 29, to vary the points of arrest of the stepping dog. A returning spring 31 for the dog rocker (see Fig. 13) is connected at one end to a tension adjusting disk 32 threaded on the left-hand screw 16 and held in its adjusted position by a lock nut 33. The free end of the spring coacts with an off-set finger 34 on the dog rocker. A plate 35 is pivoted on the left-hand screw 16 and extends into the path of movement of the finger 34 on the dog rocker. An off-set ear 36 on the plate 35 is tapped to receive a set screw 37. This screw constitutes an adjustable stop that coacts with the associate arm 17 of the supporting bracket to limit the motion of the dog rocker to normal position.

The escapement mechanism as thus far described is the same as that employed in the Remington-Noiseless No. 6 machine, and aside from being a substantially noiseless escapement, is of the "reverse feed" variety. That is to say, the carriage is "let off" for a complete letter space movement on the down stroke of the printing key. Thus, by referring to Figs. 9 to 12 inclusive, it will be understood that on the depression of a printing key, or the space key, the holding dog 20 will disengage from the tooth *a* of the escapement wheel and the stepping dog 23 will be moved into the path of the next oncoming tooth *b* of the escapement wheel as shown in Fig. 10. At this time the wheel is free to advance to the Fig. 11 position, permitting the advance of the escapement wheel and carriage a letter space distance. The return motion of the dog rocker, on the release of the depressed key, returns the dogs 20 and 23 to the normal, Fig. 12, position.

I have described in detail this escapement mechanism of the Remington-Noiseless machine in order that the features to be later described of the present invention, in their co-operation with such escapement mechanism, may be clearly comprehended. It should be understood, however, that any suitable escapement devices whether of the "ordinary" or "reverse" type, may be employed in combination with the controlling means which I will now describe.

In the present instance the escapement is controlled wholly by an actuation of the dog rocker in the manner described, from a universal bar which is controlled by the printing keys and from a trip-off actuating device cooperative directly with the dog rocker and controlled by a separate train of connections from the space key.

The type actions of the machine are of the usual construction employed in the Reming-

ton-Noiseless No. 6 machine, but it is necessary to describe them somewhat in detail and the manner in which the escapement mechanism is controlled thereby, in order to arrive at an understanding of the present invention. In said machine two printing keys are associated with each type bar to selectively actuate it to print from one or another type, depending on the key actuated. For the purpose of the present invention, however, it is merely necessary to consider the operation of the type bar from a single key, which may be either of the associated keys ordinarily employed; it being understood that the operation is the same, so far as the escapement mechanism is concerned, for all printing keys. The key lever 38 carries a printing key 39 and is connected through a link 40 with a sub-lever 41. This sub-lever and the associated key lever are limited in their depression by a stop 42. The sub-lever 41 coacts with an arm 43 of an angular actuating or driving lever 44 pivotally connected at 45 to a momentum accumulator 46, one arm of which is pivoted at 47 to a member 48 of a toggle, the other member 49 of which is connected at 50 to the type bar 51. The type bar is mounted on links 52 and 53 for movement to the printing position. The lever 44 carries a depending actuating device 54 bifurcated to straddle a curved universal bar 55 and shown in the present construction with considerable lost motion before the universal bar is taken up thereby. This universal bar forms part of a frame pivotally connected to and supported on links 57 and 58. A central depending arm 59 on the universal bar frame is pivoted to a crank arm 60 on a rock shaft 61. There are two additional arms 62 on the universal bar frame, each pivotally connected at 63 to a crank arm 64 on the rock shaft 61, and which corresponds to the crank arm 60 but is located near an end of the shaft 61. In this manner the universal bar is supported for up and down movement for transmitting a rocking movement to the shaft 61. A depending crank arm 65 on the rock shaft 61 is connected to a rearwardly extending pull link or rod 66, the rear end of which passes freely through an opening in a depending arm 67 on the dog rocker. An adjustable nut or contact 66^a is threaded on the rear end of the pull rod 66 to transmit its forward pull to the dog rocker. A lock nut holds the nut 66^a in its adjusted position. The dog rocker spring 31 exerts its force to return the dog rocker, the universal bar and the intermediate connections to normal position.

In actuating a printing key it is, we will say, depressed to the limit of its movement, as shown in Fig. 2. When the sub-lever 41 reaches the limit of its operating movement, as shown in this figure, the lost motion be-

tween the universal bar actuating device 54 and the universal bar 55 will be taken up and the actuating lever 44 will continue its movement by the momentum of said lever and the parts connected therewith. This will result in completing the movement of the toggle members 48, 49 to substantially a straight line position, causing the type bar to continue its movement to printing position, as indicated by the dotted line showing in Fig. 2. It is during this movement by momentum of the lever 44 and parts connected therewith that the device 54 coacts with the universal bar 55 to actuate it and thus operate the escapement mechanism and permit the carriage to receive a letter feed movement. It will be understood that this movement of the type bar from the full to the dotted line position in Fig. 2, is so rapidly effected that the imprint is produced before the carriage receives its letter-space step. It also will be understood from what has been said that should an operator hold the printing key 39 down, as shown in Fig. 2, the universal bar, after completing its movement to effect an operation of the escapement mechanism and a step of the carriage, will return to the normal position shown in said figure, so that said universal bar and the escapement controlled thereby may be actuated indefinitely by the space key, as will presently appear.

The space key 68 is mounted on arms 69 fixed on a rock shaft 70, the space key being shown in the position indicated because of the lack of space to show said key in the position it occupies in front of the keyboard. The shaft 70 is supported at its ends on pivot screws 71 threaded through tapped openings in bracket arms 72. An upwardly and rearwardly extending crank arm 73 is fixed on the rock shaft 70 and has the forward end of a substantially horizontally disposed pull link 74 pivoted thereto by adjustable means, as will be hereinafter described. This link extends fore and aft of the machine and is pivoted at its rear end to an upright trip-off or actuating device 76, as indicated at 77. This device is in the nature of an upstanding lever arm connected intermediate its ends to the link 74 and mounted at its lower end for pivotal and also for bodily sliding movement. Thus, the device 76 has an inclined slot 78 in the lower end thereof in which is received a headed pivot pin 79 that projects laterally from a support which, in the present instance, is in the nature of a sheet metal plate 80. This plate preferably is adjustably secured by two screws 81 and 82 to a depending arm 83 formed on the escapement bracket 14, 17, 18. The screw 82 is in the nature of a pivot screw around which the plate 80 may be adjusted to raise or lower the pivot 79 and the trip-off device 76 car.

ried thereby. The screw 82 is firmly secured in place by a lock nut (not shown) on the opposite side of the bracket arm 83. The screw 81 is in the nature of a headed clamping screw secured to the bracket arm 83 in the same manner as the screw 82. The stem of the screw 81 passes freely through a slot 84 in the plate 80 and permits the hereinbefore described adjustment of the plate 80 when the screw 81 is loosened. Said screw, however, when tightened holds the plate securely in its adjusted position. The link 74 has an off-set depending arm 74^a extending therefrom, and to the free end of the arm is connected one end of a comparatively light contractile spring d. This spring extends upwardly and rearwardly and is anchored at its upper end on an extension of the pivot pin 79. The force of this spring tends to lift the rear end of link 74, and the actuating device 76 connected therewith, and also tends to return the link 74 rearwardly to normal position. The upper free end portion of the arm 76 is provided at the front side with a curved contact or cam face or edge 85 that terminates in a point 86 from which extends a second inclined contact face or edge 87 on the rear of the actuating device. In the forward movement of the device 76 from the normal Fig. 4 position during the depression of the space key 68, the face 85 of said device will be brought into contact with an anti-friction roller 88 mounted on an arm 89 of the dog rocker 15 and move the latter the full extent of its movement from normal position, as represented in Fig. 5. This figure shows the parts as they appear just before the point 86 has passed forward of the roller and released it and the dog rocker for independent return movement to the normal Fig. 6 position. This last mentioned figure shows the parts as they appear after the space key has reached the limit of its depression where it is arrested by a padded stop 90, as shown in Fig. 1. It will be understood that at this time the dog rocker is in its normal position after having permitted a letter space advance of the carriage at the downstroke of the space key, and is in position to be actuated by an operation of a printing key, notwithstanding the space key is held depressed, as shown in Fig. 1. During the operation of the dog rocker by the depression of the space bar as just described the actuating member or device 76 receives only a pivotal movement, as will be understood from a comparison of Figs. 4, 5 and 6. This is due to the construction and relative arrangement of the parts, and to the slight up-pull of the spring d on the link 74, which is transmitted to the member 76 and tends to hold said member so that the wall forming the lower end of the inclined slot 78 will bear against the pivot pin 79. When,

however, the operator releases the space key and enables it to return to normal position with the aid of its returning spring 91 and the spring d the inclined face 87 of the member 76 will coact with roller 88 on the previously returned dog rocker, and said member 76 will receive a sliding movement on its pivot 79 from the Fig. 6 to the Fig. 7 position. This is due to the fact that the contact face 87 at this time is exerting a force substantially against a dead centered resistance of the pivots 16 of the dog rocker, which results in the dog rocker not being actuated. But it also results in wedging or camming the member 76 with a sliding action on its pivot 79 to a lowered position by the reaction of the spring 91 which overcomes the comparatively light force of the spring d. Otherwise expressed, the member 76 in returning to normal position has its pivotal movement at the upper end arrested by the dog rocker or the roller 88 thereon. At this time the reaction of the spring 91 will be exerted on said member to displace it with a cammed sliding movement on its pivot 79 against the power of the spring d. When this sliding movement is completed the parts reach substantially the position shown in Fig. 7. This last mentioned figure shows the parts as they are disposed just before the point 86 on the actuating member passes the roller in the return movement of said member to the normal Fig. 4 position. By considering Figs. 4, 5, 6 and 7 and the line e, which passes through the pivots 16 of the dog rocker, it will be seen that the member 76 in returning to normal position does not actuate the dog rocker and that as soon as said member passes rearwardly from the Fig. 7 position the spring 91 will no longer be effective to overcome the force of the spring d, which will then cause the member to slide up and bring the lower end wall of the slot 78 seated against the pivot pin 79 by the time, or before, the actuating member reaches the normal, Fig. 4, position. Said member is therefore restored to position, where on its next forward pivotal movement it will actuate the dog rocker.

It will be understood that the positions of the parts of the escapement mechanism represented in Figs. 9, 10, and 12 correspond with the parts as they are shown in Figs. 4, 5 and 6 respectively when the escapement mechanism is controlled by the space key, and that the representation of the cycle of movements of the escapement devices shown in Figs. 9, 10, 11 and 12 is the same whether the control is by a printing key or the space key, although separate and distinct trains of connections are employed from said keys.

Referring more particularly to Fig. 14 it will be seen that the pivot connection between the crank arm 72 and the link 74 is

adjustable to adjust the link forward or backward on the arm 73. The parts of said connection include an eccentric 92 having a hexagonal head 93 by which it may be turned. This eccentric is received in a opening 94 in the forward end of the link 74. An eccentrically located opening 95 extends through the eccentric 92 for the reception of a headed binding screw 96. The threaded end of this screw is received in a tapped opening 97 in the arm 73 and extends beyond the left-hand side of said arm where it receives a lock nut 98. By turning the eccentric 92 the link 74 may be shifted slightly forward or backward on the arm 73, thereby determining the normal fore and aft position of the actuating member 76 and thus regulate the timing of the pickup and release of the dog rocker by said member. When the eccentric 92 has been adjusted to proper position a tightening of the screw will bind and hold the eccentric against accidental displacement from such position of adjustment. The lock nut 98 is then tightened to hold the screw firmly against accidental movement out of binding engagement with the eccentric.

To further regulate the action of the member 76 on the roller 88, the up and down adjustment of the pivot 79 by the plate 80, as hereinbefore described, is availed of. The purpose of this particular adjustment is to determine the extent of motion transmitted to the dog rocker at each throw of the trip-off device 76, whereas the separate and distinct adjustment 92 determines the points in the throw of the trip-off device when the dog rocker is picked up and released, as hereinbefore indicated. It is essential that these adjustments be separately and independently effected in order to obtain the desired results. Therefore, the action of the tip-off mechanism from the space key may be nicely timed and regulated to obtain the desired results independently of the timing of the operation of the escapement by the printing keys and without interfering therewith.

It will be seen from the foregoing that I have provided simple and highly effective means that enable the carriage to be advanced under the operation of a printing key while the space key is held depressed, and that conversely the carriage may be advanced by the actuation of the space key while a printing key is held depressed.

While various changes may be made in the construction, and certain features thereof may be employed without others, without departing from my invention as it is defined in the accompanying claims, nevertheless from certain aspects it is an important factor of the present invention that I am enabled, with but slight changes in the existing machines, such as

the No. 6 Remington-Noiseless machine, to embody the present invention therein, even though the invention is not restricted to its inclusion in such machines.

What I claim as new and desire to secure by Letters Patent, is:—

1. The combination of a carriage, escapement mechanism therefor including a dog rocker, a type bar, a printing key, intermediate actuating connections between said printing key and type bar that are actuated by the force exerted on the printing key and enable the type bar to continue its motion to the printing position and then move back from said printing position while the printing key is maintained at the lowest point of its dip, a universal bar actuated by the continued motion of certain of said intermediate actuating connections, operative connections intermediate said universal bar and dog rocker to rock the latter by the universal bar and to permit an actuation of the dog rocker independently of said universal bar, a space key, an actuating member mounted for bodily sliding and pivotal movement and operable directly on said dog rocker to actuate it and permit an independent return movement of the dog rocker to normal position, said actuating member receiving a pivotal movement to actuate the dog rocker and receiving a sliding movement to avoid actuating the dog rocker in the return of the actuating member to normal position, and independent connections between said space key and said actuating member, whereby the dog rocker may be actuated by the space key while the printing key is held at the lowest point of its dip and the dog rocker may be actuated by the printing key while the space key is held depressed.

2. The combination of a carriage, escapement mechanism therefor including a dog rocker, a type bar, a printing key, intermediate actuating connections between said printing key and type bar that are actuated by the force exerted on the printing key and enable the type bar to continue its motion to the printing position and then move back from said printing position while the printing key is maintained at the lowest point of its dip, a universal bar actuated by the continued motion of certain of said intermediate actuating connections, operative connections intermediate said universal bar and dog rocker to rock the latter by the universal bar and to permit an actuation of the dog rocker independently of said universal bar, a space key, a pull-link that extends fore and aft of the machine and which is actuated by said space key independently of the universal bar, a downwardly extending arm on said pull-link, an upright actuating member to which said pull-link is pivoted, said actuating member being mounted for sliding as well

- as for pivotal movement and acting directly on the dog rocker by a pivotal movement to operate the dog rocker and permit an independent return movement thereof, said member receiving a sliding movement during its return to normal position to clear the dog rocker without actuating it, and a spring connected to said downwardly extending arm and exerting its force to return the pull-link and the parts connected thereto to normal position and also tending to prevent a sliding movement of the actuating member during the actuation of the dog rocker thereby.
3. The combination of a carriage, escapement mechanism therefor including a dog rocker, a type bar, a printing key, intermediate actuating connections between said printing key and type bar that are actuated by the force exerted on the printing key and enable the type bar to continue its motion to the printing position and then move back from said printing position while the printing key is maintained at the lowest point of its dip, a universal bar actuated by the continued motion of certain of said intermediate actuating connections, operative connections intermediate said universal bar and dog rocker to rock the latter by the universal bar and to permit an actuation of the dog rocker independently of said universal bar, a space key, a substantially horizontally disposed pull-link which is actuated by said space key independently of the universal bar, a downwardly extending arm on said pull-link, an upright actuating member to which said pull-link is pivoted, said actuating member being mounted for sliding as well as for pivotal movement and acting directly on the dog rocker by a pivotal movement to operate the dog rocker and permit an independent return movement thereof, said member receiving a sliding movement during its return to normal position to clear the dog rocker without actuating it, and a spring connected to said downwardly extending arm and exerting its force to return the pull-link and the parts connected thereto to normal position and also tending to prevent a sliding movement of the actuating member during the actuation of the dog rocker thereby.
4. The combination of a carriage, escapement mechanism therefor including a dog rocker, a type bar; a printing key; means controlled thereby for actuating said type bar by the force exerted on the printing key; a universal bar actuated at each operation of said printing key; intermediate connections between said universal bar and dog rocker for actuating the latter from the former and for affording an independent actuation of the dog rocker; a space key; and independent actuating connections from the space key to the dog rocker for actuating the dog rocker and for affording an independent actuation of the dog rocker by the universal bar, said independent actuating connections comprising a pull-link that extends fore and aft of the machine and which is actuated by said space key independently of the universal bar, a downwardly extending arm on said pull-link, an upright actuating member to which said pull-link is pivoted, said actuating member being mounted for sliding as well as for pivotal movement and acting directly on the dog rocker by a pivotal movement to operate the dog rocker and permit an independent return movement thereof, said member receiving a

sliding movement during its return to normal position to clear the dog rocker without actuating it, and a spring connected to said downwardly extending arm and exerting its force to return the pull-link and the parts connected thereto to normal position and also tending to prevent a sliding movement of the actuating member during the actuation of the dog rocker thereby.

6. The combination of a carriage, escapement mechanism therefor including a dog rocker, a type bar, a printing key, means controlled thereby for actuating said type bar by the force exerted on the printing key, a universal bar actuated at each operation of said printing key, intermediate connections between said universal bar and dog rocker for actuating the latter from the former and for affording an independent actuation of the dog rocker, a space key, and independent actuating connections from the space key to the dog rocker for actuating the dog rocker and for affording an independent actuation of the dog rocker by the universal bar, said independent actuating connections comprising a substantially disposed pull-link which is actuated by said space key independently of the universal bar, a downwardly extending arm on said pull-link, an upright actuating member to which said pull-link is pivoted, said actuating member having a bearing slot in which a fixed pivot is received and on which said member is mounted for sliding as well as for pivotal movement and acting by a pivotal movement on an anti-friction roller carried by the dog rocker to operate it and permit an independent return movement thereof, said member receiving a sliding movement on its pivot during its return to normal position to clear the dog rocker without actuating it, and a spring connected to said downwardly extending arm and exerting its force to return the pull link and the parts connected thereto to normal position and also tending to lift and prevent a sliding movement of the actuating member during the actuation of the dog rocker thereby.

7. The combination of a carriage, escapement mechanism therefor, and key controlled means for said escapement mechanism including a trip-off device that releases the actuated part controlled thereby before said trip-off device has completed its actuating movement thus affording an independent return movement of the actuated part, a pivot pin on which said device is supported for pivotal actuating movement and sliding clearing movement in the return thereof, and means for adjusting said pivot pin to different set positions.

8. The combination of a carriage, escapement mechanism therefor including a dog rocker, and key controlled actuating means

for said dog rocker including a trip-off device coacting therewith and that releases the dog rocker before said trip-off device has completed its actuating movement thus affording an independent return movement of the dog rocker, a pin on which said device is supported for pivotal and sliding movement, means for adjusting said pin to different set positions, and independently adjustable means in the actuating means for said trip-off device to vary its normal position around said pin.

Signed at Middletown, in the county of Middlesex and State of Connecticut this 28th day of October A. D. 1927.
